UNITED STATES PATENT OFFICE

LEO M. CHAPMAN, OF CHICAGO, ILLINOIS

DESIGN FOR A STREET SIGN FRAME FOR LAMP POSTS

Application filed August 12, 1932. Serial No. 44,584. Term of patent 14 years.

To all whom it may concern:

Be it known that I, LEO M. CHAPMAN, a citizen of the United States, residing at Chicago, in the county of Cook and State of Illinois, have invented a new, original, and ornamental Design for Street Sign Frames for Lamp Posts, of which the following is a specification, reference being had to the accompanying drawing, forming part thereof.

Figure 1 is a corner or diagonal view of my new street sign frame.

Figure 2 is a side view showing one of the four sides.

Figure 3 is a perspective view showing the entire frame.

The leading feature of my design consists of the triangular shaped corner pieces 10 which are joined by the channel bars 11.

I claim:

The ornamental design for a street sign frame for lamp posts as shown and described.

LEO M. CHAPMAN.
